W. L. KRON.
PROTECTOR FOR AUTOMOBILE RADIATORS.
APPLICATION FILED JUNE 21, 1915.

1,193,702.

Patented Aug. 8, 1916.

UNITED STATES PATENT OFFICE.

WALTER L. KRON, OF LA FAYETTE, INDIANA. ASSIGNOR OF ONE-THIRD TO JAMES S. McDONIELS AND ONE-THIRD TO WILLIAM McDONIELS, OF LA FAYETTE, INDIANA.

PROTECTOR FOR AUTOMOBILE-RADIATORS.

1,193,702.

Specification of Letters Patent. Patented Aug. 8, 1916.

Application filed June 21, 1915. Serial No. 35,441.

To all whom it may concern:

Be it known that I, WALTER L. KRON, a citizen of the United States, residing at La Fayette, in the county of Tippecanoe and State of Indiana, have invented certain new and useful Improvements in Protectors for Automobile-Radiators, of which the following is a specification.

The object of this invention is to provide a protector or hood to prevent the radiation of heat from the radiators of automobiles, the object being to protect the radiator against the freezing of the liquid contained therein while the automobile is standing idle in freezing weather.

Another object of the invention is to provide a protector that can be easily put in position on the radiator and removed therefrom, and which does not interfere with any of the parts or fastenings of the hood.

Another object of the invention is to provide an improved fastening device therefor to hold the protector in place.

These and other objects of the invention will be fully illustrated in the drawings, described in the specification and pointed out in the claims at the end thereof.

In the drawings, Figure 1 is a perspective view of the bonnet and radiator of an automobile showing the protector in place. Fig. 2 is a vertical section through the protector, the section being taken on the line 2^x—2^x of Fig. 1. Fig. 3 is a horizontal section through the protector, the section being taken on the line 3^x—3^x of Fig. 2. Fig. 4 is a horizontal section through the protector, the section being taken on the line 4^x—4^x of Fig. 2.

In the drawings reference numeral 1 indicates the bonnet of an automobile and 2 indicates the radiator. For the radiator is provided the protector 3 which may be described as follows: The radiator protector comprises a shell 4 formed of a single piece of metal bent to conform to the outline of the sides and top of the radiator. This shell has a flange 5 on the front edge thereof extending inwardly around the front edge thereof. To this flange 5 is connected the plate 15 which closes the opening in the front of the protector at the top. This plate is formed of a single sheet bent double with the lower edge formed as shown in section

at the top of Fig. 2, the front edge being turned in on itself at the bottom and the rear edge being bent rearwardly and down to form a groove between the two plates to receive the top of the sliding shutter 11 when it is at the top of the protector. At the sides the inner edge of the flange is bent in as shown at 6 in Fig. 3. Interlocked with this inner edge of the flange is one edge of a Z-shaped plate 7. Along the rear side of the Z-shaped plate 7 is placed a flat plate or strip 8 which projects centrally of the radiator and with the outer edge of which the Z-shaped plate 7 and the inturned flange 6 forms a groove in which the movable shutter of the radiator is held and guided. The strip 8 and the Z-shaped plate 7 are fastened each to the flange 5 by means of bolts 9. A filler 10 preferably of wood is used to fill the open space between the Z-shaped plate and the shell and flange of the radiator.

In the guides thus formed on both sides of the radiator is mounted to slide a shutter 11 which shutter is formed of two parallel metal plates with a sheet asbestos filler 12 between them. The forward metal plate is turned over the rear plate at both the top and the bottom as shown in section in Fig. 2. To the front of the shutter is fastened a handle 13 by which the shutter may be raised and lowered.

Across the bottom of the protector is placed a pad 16 which is stationary. This pad is formed of two sheets of metal with an asbestos filler between them. The lower edge of the rear sheet is turned forward as shown at 17. The upper edge of the front sheet is turned down over the rear sheet. The lower edge of the front sheet is turned forward and then down and back, as shown at 18, engaging with the forwardly turned edge of the rear sheet. In this way the sheets are held together at the top and bottom with the asbestos filler between them and a flange is formed at the bottom of the pad which serves as a stop for the sliding shutter. The back sheet of the pad is bent up reversely along the sides and with the front sheet form side flanges for the pad which overlap the Z-shaped plate 7 and by which the pad is fastened in place. Bolts 9 are used to clamp the parts together. It will be understood that

the strips 8 end at the top of the pad, the pad forming the lower part of the guide for the shutter.

The shell 4 is provided at the top with an opening to encircle the nozzle of the radiator through which water is poured into the radiator. The cap is first removed from the nozzle and the protector is then put in place. The cap is then screwed on in place holding the protector in position. If a plug is used instead of a cap to close this opening its removal will ordinarily not be necessary. The inside of the shell of the protector is lined at 20 with felt or other suitable insulating material. To the shell are attached lugs 21 and 22 to which in turn may be fastened thongs or ropes, the free ends of which may be tied to the lamp brackets of the machine. This makes it easy to put the radiator protector in place and fasten it or remove it.

When the shutter is up the circulation of air through the radiator from the front is prevented and when the shutter is down air is permitted to flow through the radiator from the front. By the use of this device the radiator can be protected against freezing up when the engine of the car is not running.

I claim.

30 1. An automobile radiator protector comprising a shell having front and rear openings, said rear opening adapted to admit the front end of the radiator to support the shell on the latter; a stationary, vertically disposed member extending across the upper front portion of the shell and having its lower edge provided with a downwardly presented horizontal channel; and a shutter having vertical side edges slidably mounted 35 in the sides of the shell, said shutter adapted to be raised and lowered relatively to said member to wholly or partially close the opening through the front of the shell, and

Copies of this patent may be obtained for five cents each, by addressing the "Commissioner of Patents, Washington, D. C."

said shutter having an upper edge to enter the channel in the lower edge of said stationary member. 45

2. An automobile radiator protector comprising a shell having front and rear openings, said rear opening adapted to admit the front end of the radiator to support the shell 50 on the latter; a stationary, vertically disposed member extending across the upper front portion of the shell having its lower edge provided with a downwardly presented horizontal channel; a pad extending across 55 the lower front portion of the radiator having a bottom horizontal flange extending forwardly; a shutter in front of said pad having vertical side edges slidably mounted in the sides of the shell, said shutter adapted to be raised and lowered relatively to said stationary member to wholly or partially close the opening in the front of the shell, and having an upper edge to enter the channel in the lower edge of said stationary 60 member, said bottom flange of the pad forming a seat against which the bottom of the shutter closes edgewise to thereby limit the downward movement of said shutter.

3. An automobile radiator protector, comprising a shell having front and rear openings, said rear opening adapted to admit the front end of a radiator to thereby support the shell thereon; upper and lower stationary members on the front of the shell 75 and vertically disposed, a shutter vertically movable between said members and adapted to close edgewise thereagainst to close and expose the front opening of the shell; and lugs on the side members of the shell for the attachment of auxiliary means by which the shell may be fastened in place on the radiator. 80

In testimony whereof I affix my signature.

WALTER L. KRON.
